United States Patent Office

Des. 211,677

Patented July 9, 1968

211,677

COMB

William N. Bulow, San Diego, Calif., assignor to Smoothy Products, Inc., Burbank, Calif., a corporation of California

Filed Oct. 6, 1966, Ser. No. 4,327

Term of patent 14 years

(Cl. D86—8)

I claim:

The ornamental design for a comb, substantially as shown.
